UNITED STATES PATENT OFFICE.

CHARLES DOCHERTY, OF BROOKLYN, NEW YORK.

MEANS FOR REMOVING ANIMALS FROM BURNING STRUCTURES.

1,081,662.

Specification of Letters Patent.

Patented Dec. 16, 1913.

Application filed December 21, 1912. Serial No. 738,106.

To all whom it may concern:

Be it known that I, CHARLES DOCHERTY, a citizen of the United States, residing at Brooklyn, in the county of Kings and State 5 of New York, have invented certain new and useful Improvements in Means for Removing Animals from Burning Structures, of which the following is a specification.

This invention comprehends certain improvements in devices for liberating animals and relates more particularly to means whereby horses may be quickly and safely led from a burning building.

The primary object of the invention resides in the provision of a novelly constructed stable equipped with means whereby a plurality of horses may be simultaneously led from their stalls to the exterior of the structure through a central aisle.

Another and more specific object of the invention resides in the provision of a vertically movable manger positioned between two series of stalls, the upward movement of said manger clearing a central aisle into 25 and through which the horses may be led.

With these and other objects in view, as will become more apparent as the description proceeds, the invention consists in certain novel features of construction, combination, and arrangement of parts, as will be hereinafter fully described and claimed.

For a complete understanding of my invention, reference is to be had to the following description and accompanying drawings, in which,

Figure 1 is a vertical sectional view through a stable, showing my improved releasing means, and, Fig. 2 is a top plan view of my invention, the roof of the stable being 40 removed.

Referring in detail to the drawings by numerals, 1 designates the roof, 2 the side walls, 3 the end walls, and 4 the bottom or floor of a stable of any desired construction.

45 A plurality of vertical partitions 5 extend transversely of the stable to one side of the longitudinal center and form a plurality of stalls. A second series of similar partitions 6 are arranged upon the other side of 50 the stable in parallel relationship to each other and to the first mentioned partitions. The outer vertical edges of the partitions terminate short of the side walls of the stable and the inner opposed edges are spaced

from one another to provide a central aisle 55 7. Doors 8 provide convenient communication to the respective stalls.

In carrying out my invention, I provide a manger generally designated 9 adapted to fit within the aisle 7 and extend the entire 60 length thereof and close, when in its lowered position, the inner ends of the stalls. The manger, as well as the partitions, is preferably made of galvanized sheet-metal and comprises the spaced upright members 10, 65 longitudinally slotted, as at 11, and formed with the feed troughs 12. The upper ends of the upright members 10 are bent outwardly in opposite directions and slotted, as at 13, to provide a rack for holding hay 70 or similar material. The ends of the manger are closed by the walls 14 to which are attached the cables 15, said cables running around sheaves 16, secured to the top 1 of the stable. A weight 17 is secured to the 75 free end of each of the cables 15 and is connected to a cable 18, which runs downwardly, then under the floor 4, over the pulleys 19, and is connected to the drum 20. When the drum is rotated in the proper direction by means of the handle 21, the manger will be raised so as to clear the aisle 7. 80

The endless cable 22 runs through the aisle 7, around the sheaves 23 and 24, which may be turned by means of the hand-wheels 85 25. The endless cable 22 is provided with the eyes 26 to which are connected the halter ropes 27, by means of the hooks 28. The slots 11 permit the halter ropes 27 and hooks 28 to pass through the uprights 10 in order 90 that said hooks may be connected to the eyes 26.

In case of fire, the drum 20 is rotated so as to cause the manger 9 to be lifted out of the aisle 7. When this has been done, one 95 of the hand-wheels 25 is turned so as to draw the endless cable 22 through the aisle 7 and since the horses are connected to said cable, they will follow the same and be led safely from the burning structure. Fires very 100 often start in the hay holding portions of the mangers and it is for this reason that I provide a movable manger rather than movable stall partitions. Should the hay which the horses are eating catch on fire, the manger 105 is raised and carries the burning hay or similar material from the sight of the horses and thus the animals can be more easily led

from danger than would be the case should the burning material remain before their eyes.

It is to be understood that while I have shown and described the preferred embodiment of my invention, I do not wish to be limited to this exact construction, combination, and arrangement of parts, but may make such changes as will fall within the spirit and scope of the invention.

Having thus described my invention, what I claim is:—

- 1: The combination with a plurality of stalls communicating with a central aisle, of a manger extending longitudinally of said aisle and closing the inner ends of the stalls, and means for raising said manger from the aisle.
2. The combination with a plurality of stalls arranged upon opposite sides of a central aisle and communicating therewith, of a manger positioned within said aisle and closing the inner ends of the stalls, means for raising said manger, and means for leading animals from said stalls into and through said aisle.
3. In a device of the character described, the combination with a building having a series of vertical partitions arranged along

opposite sides thereof, said partitions forming stalls which communicate with an aisle, a manger positioned within said aisle and closing the inner ends of the stalls, flexible members connected to said manger, sheaves secured to the top of the stable over which said flexible members pass, weights connected to the free end of said flexible members, means connected with said weights for lowering the same whereby the manger will be raised, an endless cable running through said aisle, and means to secure animals to said cable.

4. In combination, a plurality of stalls opening upon a central aisle, a vertically movable manger positioned within said aisle and closing the inner ends of the stalls, said manger including slotted supporting members, means movable between said supporting members, means movable between said supporting members for leading animals through the aisle, and halter ropes extending through said slots and connected to said means.

In testimony whereof I affix my signature in presence of two witnesses.

CHARLES DOCHERTY.
